UNITED STATES PATENT OFFICE.

GEORGE F. SULLIVAN, OF CAMBRIDGE, MASSACHUSETTS.

CHUCK FOR WEB-SPINDLES.

1,136,627.

Specification of Letters Patent. Patented Apr. 20, 1915.

Application filed June 12, 1913. Serial No. 773,244.

To all whom it may concern:

Be it known that I, GEORGE F. SULLIVAN, a citizen of the United States, and a resident of Cambridge, in the county of Middlesex and State of Massachusetts, have invented certain new and useful Improvements in Chucks for Web-Spindles, of which the following is a specification.

This invention relates to means for securing a tubular core carrying a rolled up web of paper for use in a printing press, to the shaft or spindle which supports the web on the press.

The invention is embodied in a chuck adapted to be firmly engaged with the tubular core, the chuck being preferably double acting so that it is engageable simultaneously with the core and with the spindle.

Of the accompanying drawings:—Figure 1 represents a side elevation of a chuck embodying my invention, and of a portion of the spindle, portions of the core and of the web thereon being shown in section. Fig. 2 represents a section on line 2—2 of Fig. 1. Fig. 3 represents a section on line 3—3 of Fig. 2. Fig. 4 represents a section on line 4—4 of Fig. 3. Fig. 5 represents an edge view of the cam ring hereinafter referred to. Figs. 6 and 7 are detail views similar to a portion of Fig. 3, illustrating a modification herein-after described. Fig. 8 is a perspective view of one of the struts shown in Figs. 6 and 7.

The same reference characters indicate the same parts of all the figures.

In the drawings:—12 represents a rotary shaft or spindle adapted to rotate in bearings on the frame of a printing press, and 13 represents a tubular core of metal or fibrous material on which a web of paper 14 is wound.

15 represents the body of my improved chuck, the same being a sleeve adapted to receive the spindle 12, and to enter the core 13, a portion of the said body being preferably enlarged to form a head which may be composed of an outer portion or flange 15^a integral with the portion which enters the core, and an inner portion 16 attached by screws 17 to the flange 15^a. The sleeve is provided with longitudinal slots 18 which preferably extend through the entire thickness of the wall of the sleeve excepting at the end portions of the slots where their continuity is interrupted by bridges integral with the portions 15 and 16 and provided with inclined faces 19. Outer keys 20 are movable longitudinally in the slots

18, and are provided on their inner edges with inclined faces 21 bearing on the faces 19, said faces 19 and 21 constituting complementary means whereby when the keys are moved longitudinally in the direction of the arrow α , Fig. 3, they are also moved radially outward and caused to engage the inner surface of the core 13, the outer edges of the keys being provided with gripping angles preferably formed by imparting a transverse curvature to said outer faces as shown by Fig. 4. The keys 20 are movable simultaneously and positively in the direction of the arrow α by a cam ring 23 having cam faces 24 against which the inner ends of the keys are pressed by springs 25, Fig. 3.

The ring 23 is adapted to be rotated in a chamber or bearing formed in the head portion 15^a, and is provided with a gear 26, Fig. 5, meshing with a pinion 27 on a radial stud 28 which is journaled in a bearing 29 in the enlarged portion of the sleeve and is provided with a squared head 30 adapted to be engaged and rotated by a wrench.

The rotation of the cam ring in one direction causes the cam faces to positively move the keys 20 in the direction of the arrow α , thus engaging the keys with the core, and its rotation in the opposite direction permits the springs 25 to move the keys in the opposite direction, thus releasing the keys from gripping engagement with the core.

While the sleeve 15 may be engaged with the spindle 12 by any suitable means, I prefer to cause such engagement by the means next described.

In the open portions of the slots 18 between the bridges on which the inclines 19 are formed, are inner keys 32 which are connected with said bridges by flexible spring strips 33 which permit the inner keys to move radially inward and prevent them from moving longitudinally. The inner keys 32 have inclined faces 35 on their outer edges on which bear similarly inclined faces 36 on the inner edges of the outer keys 19. The inner keys have gripping angles on their inner edges adapted to engage the spindle 12. It will now be seen that when the outer keys are moved in the direction of the arrow α , the inner keys are moved radially inward by the movement of the inclined faces 36 on the inclined faces 35, the inner keys being therefore engaged with the spindle by the operation of engaging the outer keys with the core.

Instead of employing the coacting in-

clined faces 19, 21, 35, 36, I may provide swinging struts 37, as shown in Figs. 6, 7, and 8, the keys 20^x and 32^x being provided with recesses to form bearings for the ends 5 of said struts, so that when the outer keys are moved longitudinally in the manner hereinbefore described, they engage the inner surface of the core 13 while the inner keys engage the spindle 12. With either 10 form, the keys engage and bind throughout their entire length and firmly and rigidly secure the core and its roll to the shaft or spindle.

I claim:—

15 1. A double acting chuck comprising a sleeve having longitudinal slots, inner and outer keys movable in said slots, yielding means preventing longitudinal movement of the inner keys, the inner keys being movable 20 radially inward and immovable longitudinally, while the outer keys are movable radially outward and longitudinally, and means for positively moving the outer keys longitudinally in one direction, the sleeve 25 and keys being provided with complementary means whereby said longitudinal movement of the outer keys is caused to simultaneously move the inner keys radially inward and the outer keys radially outward.

30 2. A double acting chuck comprising a sleeve having longitudinal slots, inner and outer keys movable in said slots, yielding means preventing longitudinal movement of the inner keys, the inner keys being movable 35 radially inward and immovable longitudinally, while the outer keys are movable radially outward and longitudinally, and a cam ring movable in the sleeve and having cam faces adapted to move the outer keys longitudinally in one direction, the sleeve and 40 keys being provided with complementary means whereby said longitudinal movement of the outer keys is caused to simultaneously move the inner keys radially inward and the outer keys radially outward.

45 3. A double acting chuck comprising a sleeve having longitudinal slots, inner and outer keys movable in said slots, yielding means preventing longitudinal movement of the inner keys, the inner keys being movable 50 radially inward and immovable longitudinally, while the outer keys are movable radially outward and longitudinally, and a cam ring movable in the sleeve and having cam faces adapted to move the outer keys longitudinally in one direction, the sleeve and keys 55 being provided with complementary means whereby said longitudinal movement of the outer keys is caused to simultaneously move the inner keys radially inward and the outer keys radially outward, means being provided for yieldingly holding the outer keys 60 against the cam ring.

4. A double acting chuck comprising a sleeve having longitudinal slots and spaced 65 apart bridges extending across the end portions of the slots, inner keys located in said slots between the bridges and having bearings, yielding connections between the inner keys and the bridges which permit radial inward movement of said keys and prevent longitudinal movement thereof, outer keys longitudinally movable in said slots and having bearings, swinging struts fitting between the bearings of the inner and outer 70 keys, and means carried by the sleeve for moving the outer keys longitudinally in one direction, said movement causing the inner keys to move radially inward and the outer keys to move radially outward. 75

5. A double acting chuck comprising a sleeve having longitudinal slots and spaced apart bridges extending across the end portions of the slots, inner keys located in said slots between the bridges and having bearings in their outer sides, yielding connections between the inner keys and the bridges which permit radial inward movement of said keys and prevent longitudinal movement thereof, outer keys longitudinally movable in said slots and having bearings in 80 their inner sides, swinging struts fitting between the bearings of the inner and outer keys, a cam ring movable in the sleeve and having cam faces bearing on the outer keys 85 and adapted to move the same endwise in one direction, springs yieldingly holding the outer keys against the cam ring, and means for partially rotating said ring. 90

6. A double acting chuck comprising a 100 sleeve having longitudinal slots and spaced apart bridges extending across the end portions of the slots, inner keys located in said slots between the bridges and having bearings, yielding connections between the inner 105 keys and the bridges which permit radial inward movement of said keys and prevent longitudinal movement thereof, outer keys longitudinally movable in said slots and having bearings, swinging struts fitting between the bearings of the inner and outer keys, a cam ring movable in the sleeve and having cam faces bearing on the outer keys 110 and adapted to move the same endwise in one direction, springs yieldingly holding the outer keys against the cam ring, said ring being provided with a segmental rack, and a radial stud journaled in the sleeve and provided with a pinion meshing with said rack. 115

In testimony whereof I have affixed my 120 signature, in presence of two witnesses.

GEORGE F. SULLIVAN.
